FIG. 1 is a perspective view of a portable porous construction
mat according to the new design;

FIG. 2 is another perspective view thereof;

FIG. 3 is a front view of FIG. 1;

FIG. 4 is a rear view of FIG. 1;

FIG. 5 is a right side view of FIG. 1;

FIG. 6 is a left side view of FIG. 1;

FIG. 7 is a top view of FIG. 1; and,

FIG. 8 is a bottom view of FIG. 1.

The phantom lines shown in parts of the designs are included
for purposes of illustrating optional features and form no part
of the claimed design.
